UNITED STATES PATENT OFFICE.

AUGUST MARTIN AND HENRY H. DOERING, OF CHICAGO, ILLINOIS; SAID DOERING
ASSIGNOR TO SAID MARTIN.

EGG-TREATING MACHINE.

1,312,337.

Specification of Letters Patent. Patented Aug. 5, 1919.

Application filed June 5, 1916. Serial No. 238,263.

To all whom it may concern:

Be it known that we, AUGUST MARTIN and HENRY H. DOERING, citizens of the United States, and residents of Chicago, in the 5 county of Cook and State of Illinois, have invented certain new and useful Improvements in Egg-Treating Machines, of which the following is a description, reference being had to the accompanying drawings, 10 which form a part of our specification.

Our invention relates to a machine for sterilizing and preserving eggs by immersing them in liquid preparations which are heated to predetermined degrees of temperature; the invention contemplating a suitable apparatus, which is preferably manually operated, whereby a number of eggs may be simultaneously treated, as will be more fully comprehended from the following detailed 15 description of the drawings, wherein:—

Figure 1 is a partial front elevation and vertical sectional view of our improved machine.

Fig. 2 is a vertical sectional view, taken 25 on the line 2—2 of Fig. 1 looking in the direction of the arrows; the figure being on a larger scale than Fig. 1.

Fig. 3 is a detail perspective view of a portion of the operating mechanism disposed on the rear side of the machine.

Fig. 4 is a perspective view of a portion of the machine illustrating a modified form of operating mechanism.

Fig. 5 is a vertical sectional view of the 35 construction shown in Fig. 4 looking toward the operating mechanism of the machine.

In the exemplification of the invention, the machine or apparatus is preferably shown as manually operated; the machine 40 comprising a suitable tank portion 10, preferably constructed of metal so as to provide a plurality of fluid-tight compartments or chambers which are subjected to heat in order that the sterilizing and preserving 45 fluid contents of the compartments of the tank may be maintained at the desired temperatures.

The tank-portion 10 of the machine is 50 preferably of such length as to provide at least a pair of chambers or compartments 11 and 12, which are preferably separated from each other by means of an air-chamber or space 13, in order that the compartments may be insulated from each other; or this 55 may be accomplished by any other suitable

heat-insulating means. The tank-portion of the machine is mounted on a suitable supporting frame comprising the uprights or legs 14 formed of angle iron or any other suitable members; the uprights or legs being 60 reinforced and secured together adjacent the lower ends thereof by cross-members 15.

The front side of the machine at a central point intermediate of the ends is shown provided with a pair of parallelly disposed 65 angle members 16, 16 arranged in slight separated relation so as to provide a guide-way for a foot-treadle or operating lever 17. The foot-treadle is provided at the front of the machine with a suitable foot-rest portion 70 18 and the treadle is disposed beneath the tank-portion of the apparatus toward the rear side of the machine where it terminates in, or is connected with, the vertically disposed rod 19 extending toward the top of 75 the machine and operatively secured to a cross-bar or member 20, see Fig. 3.

The vertically disposed rod 19 is preferably square in cross-section and made to pass through suitable brackets or guide 80 members 21 and 22 secured to the rear side of the tank-portion of the machine, as shown in Fig. 3; the brackets or guide members 21 and 22 being made to conform with the cross-sectional contour of the rod 19 and 85 thus prevent any possibility of the rod rotating about its own axis.

At a suitable point, to-wit preferably beneath the bracket or guide 21, the rod 19 of the foot-treadle or operating lever is provided with a lug or arm 23 shown disposed at right angles to the rod-portion of the foot-treadle; with the outer end of the lug or arm shown provided with a cross-arm or transversely disposed lugs 24. The ends of 90 the lugs 24 are provided with apertures to receive the ends of the two springs 25, 25, whose opposite ends are secured to suitable members or eye-bolts 26 extending through suitable apertures in the bars or frame members 27 which are secured to the cross-bar or frame member 28. The cross-bar 28 is maintained in position by suitable uprights or rods 29 which are secured in any suitable manner to the rear side of the tank portion 10 of the machine. The eye-bolts or members 26 may be vertically adjusted in the apertures in bars 27, by screwing the same through the nuts with which their threaded ends are provided; the nuts being preferably dis- 110

posed on both sides of bars 27, thus enabling the tension of the springs 25, 25 to be increased or decreased as desired; the springs being adapted to draw the rod 19, and therefore also foot-treadle 17, upward into the raised and normal position of the operating mechanism shown in Fig. 2. The upward movement of the treadle will be limited by contact of the cross-bar or member 20 coming into contact with cross-bar or member 28.

Each compartment or chamber 11 and 12 is provided with a skeleton tray or plunger member 30; the trays 30 being secured to upright straps or bars 31. The upper ends of these straps or bars are shown bent rearwardly, see Figs. 2 and 3, and provided with apertures for the passage of posts or supporting members 29 alined with the apertures.

The trays or plunger members 30 consist of open rectangular frames provided with angle-bars 32, 32 arranged in parallel relation across the top from side to side to provide a guide-way and support for a suitable wire-basket or foraminated egg-holding container not shown, and which has previously been filled with the eggs to be treated; the baskets or containers when charged being placed on the stationary shelves 33 arranged at the ends of the machine, adjacent the top of the tank-portion. The shelves 33 are so positioned as to enable the baskets to be slid onto the guide-ways 32 of the trays or plunger members 30; the bars 32 insuring the proper placing of the baskets to permit operation of the machine.

In order to reinforce and properly support the forward side of the tray or plunger member 30, we have shown the straps 31 extending slightly below the tray or open frame of each compartment, with the lower ends provided with the diagonally disposed brace members 34 which extend forward and are secured to the front side of the trays or open frame, as shown in Fig. 2.

Disposed longitudinally beneath the tank-portion of the machine, and therefore beneath the chambers or compartments 11 and 12, are a plurality of burners 35 which are adapted to be connected with any suitable source of gas supply, controllable by suitable keys or valves, as shown at 36 in Fig. 1.

In practice, the solution or liquid contents of the one chamber or compartment is intended to be heated to a greater degree of temperature than the temperature of the contents of the other chamber or compartment, and for that reason the one chamber need merely have two burners therebeneath, while the other chamber preferably has all of the burners disposed beneath the same.

In order that the temperature of the fluid-contents of the different chambers or compartments may be ascertained, each tank end

is shown provided with a suitable thermometer, as at 37, arranged at a point where it will not interfere with the proper operation of the basket-carrying tray or plunger member; the thermometers being provided with 70 portions depending into the chambers or compartments and therefore into the fluid contents or solution.

The chambers or compartments, adjacent the bottoms thereof, are preferably provided with a suitable drain or outlet which may be in the nature of the draw-off cock or faucet shown at 38 in Fig. 2, whereby the contents of the chambers may be withdrawn when desired.

As is evident from the construction shown and described, a downward pressure on the foot-lever or treadle 17 will cause the latter to move downwardly against the actions of the springs 25; and as the foot-lever is secured to the cross-member 20, to which the basket-carrying members or trays 30 are secured by the straps 31, the downward movement of the foot-lever will cause both basket-carrying members or trays 30 to descend into their respective chambers or compartments; the bars or straps of the basket-carrying members or trays, together with cross-member 20, having guiding and sliding relation with the rear wall of the tank and the supporting members or rods 29, as previously described.

In Figs. 4 and 5, we illustrate a modified form of the machine, wherein the tank construction and its manner of support is substantially similar to the construction shown in the first figures of the drawings, with the tank portion 39 divided into several compartments or chambers having an intervening air space beneath the top portion of the tank at the point indicated at 13, similar to the construction shown in Fig. 1. In this construction the basket-carrying members or trays 30 are secured to the straps 40, a pair of straps being preferably employed for 110 each tray or basket-carrying plunger. The upper ends of the straps 40 are bent into the loop form shown in the drawings, so as to have a leg of each strap or band disposed parallel with and on opposite sides of the 115 tank portion 39 of the machine.

The rear side of the machine is provided with suitable brackets or guides 41 and the lower outer ends of the straps 41 are connected together by means of a suitable bar 120 42 so as to cause both straps 40, and therefore both trays or basket-carrying plungers 30 to move in unison.

Pivots secured, at an intermediate point to the bar 42, is a link 43 which, in 125 turn, is pivotally secured to a lever 44 disposed beneath the machine and pivoted at its forward end at the point 45 so as to permit vertical movement of the lever about the pivotal point 45. The rear end of the lever 130

44 extends beyond the point of its pivotal connection with link 43, and is there provided with a suitable coil spring 46, the other end of which is secured to an eye-bolt 5 or other suitable adjustable member 47, which latter has adjustable relation with a bracket or angle member 48 by means of butter-fly nut 49; the eye-bolt 47 passing through a suitable aperture in the bracket 10 member 48 which is secured to the rear side of the machine. At a point centrally between the ends of the machine and in vertical alinement with the lever 44, we provide a foot-treadle or lever 50 which is pivotally secured in any suitable manner, at 51, on the supporting frame of the machine; with the foot-receiving portion 52 extending forward of the machine, as shown in Fig. 5. The foot-treadle or lever 50 is operatively connected with lever 44 by means of a suitable link 53; and the upward movement of the foot-treadle, beyond a predetermined point, is limited by a suitable strap or cross-bar 15 secured in any suitable manner, at 54, on the supporting frame of the machine; with the foot-receiving portion 52 extending forward of the machine, as shown in Fig. 5. It is evident from this construction that downward pressure on the foot-treadle 50 will cause lever 44, through the medium of link 53, to be drawn downwardly against the action of spring 46 and therefore also cause the egg basket-carrying 20 plungers or trays 30 to descend into their respective chambers or compartments through the medium of straps 40 which have connection at their lower ends with the lever 44; the trays or basket-carrying plunger 25 gers being caused to move in unison.

Our improved machines, as previously stated, are especially intended for carrying out a process of preserving eggs, which contemplates the immersion of the eggs (previously placed in suitable baskets or containers) in suitable solutions whereby the eggs are sterilized and provided with a suitable sealing coating without affecting the quality of the eggs. In order to carry out 30 this process, it is necessary to immerse the eggs in solutions of different temperatures and for that reason one of the compartments of the tank portion of the machine, as for example chamber or compartment 11, with its liquid contents, is heated to a predetermined degree of temperature. The tray or basket-plunger of this chamber is depressed so as to immerse the eggs for a brief period of time in order that the same may be 35 prepared or tempered; and immediately thereafter the egg-filled basket, upon the return of the plunger or tray to normal position, is shifted onto the basket-carrying tray or plunger of the adjacent chamber or compartment, as for example chamber 12 in Fig. 1, when the foot-treadle or lever is again depressed and the eggs lowered into the second chamber or compartment which is provided with a suitable solution, heated 40 to a higher degree of temperature than the

solution in the first mentioned compartment or chamber; the tray being maintained in lowered position for a brief predetermined period of time, insufficient, however, to appreciably coagulate the albumen contents of the eggs. After the initial operation of the machine, it is evident that the first mentioned tray may be supplied with a fresh supply of eggs before the eggs on the tray of chamber 12 are immersed, so that each 45 tray or basket-carrying plunger will be provided with eggs, and a single operation of the foot-treadle or lever will result in the initial tempering as well as in the final treatment and coating of the eggs. 50

As the immersion of the eggs must continue for a very short predetermined period, the machine is preferably shown as manually operated so as to be under the full control of the operator. In view of the fact that the chambers or compartments of the tank must be heated, the tank portion of the machine is preferably formed of suitable metal; while the construction of the operating mechanism is such that but little 55 power need be exerted by the operator to manipulate the trays or plunger elements, which are automatically returned to normal position; the trays or plungers being maintained in proper alinement by the means whereby the trays or plungers are connected with the foot-treadle or lever of the machines. The chambers or compartments of the tank are preferably shown separated by 60 the air space or chamber 13, in order that the temperatures of the two chambers and their contents may be maintained at different degrees without the heat of the one being conducted through the adjacent metallic walls. 65

The constructions that have been shown and described may be varied in certain details without, however, departing from the spirit of our invention. 70

What we claim is:—

1. A machine of the class described, comprising a tank portion provided with a plurality of chambers, means whereby the chambers are insulated from each other, a tray mounted in each chamber, means whereby the trays may be moved vertically in their respective chambers, and means whereby the trays are normally maintained at the top of their respective chambers. 75
2. A machine of the class described, comprising a tank portion provided with a plurality of chambers in separated relation with each other, a tray reciprocatingly mounted in each chamber, reciprocating means whereby the trays may be moved vertically in their respective chambers, and means whereby the trays are normally maintained adjacent the tops of their respective chambers. 80
3. A machine of the class described, comprising a tank portion provided with cham- 85

bers insulated one from the other, a tray reciprocatingly mounted in each chamber, a pivotally mounted foot-lever operatively connected with all of said trays, and means whereby the foot-lever and trays are returned to normal position.

4. A machine of the class described, comprising a tank portion provided with a supporting frame, the tank portion being divided into a plurality of chambers, in spaced relation with each other, so as to provide air spaces therebetween, a plunger member reciprocatingly mounted in each chamber, operating means mounted beneath the tank portion, and means intermediate of said operating means and the plunger member whereby the latter are plunged into their respective chambers when the operating means are actuated, said last mentioned means being arranged to move on both sides of the rear wall of the tank portion so as to be guided thereby.

5. A machine of the class described, comprising a tank portion provided with a supporting frame, the tank portion being divided into a plurality of chambers insulated from each other, a tray-carrying member reciprocatingly mounted in each chamber, a foot-lever disposed beneath the tank portion, means whereby the foot-lever is operatively connected with all of said tray-carrying members, and means whereby said members and foot-lever are automatically returned to normal position.

35 6. A machine of the class described, comprising a tank portion provided with a supporting frame, the tank portion being divided into a plurality of chambers insulated

from each other, a tray reciprocatingly mounted in each chamber, a foot-lever reciprocatingly mounted beneath the tank portion, means intermediate of said foot-lever and all of said trays whereby the latter are moved downwardly into their respective chambers when the foot-lever is reciprocated, adjustable tension-applying means secured to said foot-lever and body portion of the machine whereby the foot-lever and the trays are returned to normal positions, and means whereby the contents of the chambers may be drained therefrom.

7. A machine of the class described, comprising a supporting frame, a tank portion mounted thereon, the tank portion being divided into a plurality of chambers with air spaces therebetween, a tray reciprocatingly mounted in each chamber, a foot-lever pivotally mounted beneath the tank portion, means intermediate of the foot-lever and all of said trays whereby the trays are reciprocated downwardly into their respective chambers when the foot-lever is depressed, said means having a sliding relation with the body portion of the machine to maintain the trays in proper position, a spring intermediate of the foot-lever and the body portion of the machine whereby the foot-lever and the trays are normally maintained in raised position, and means whereby the tension of said spring may be adjusted.
